FLUID TREATING APPARATUS FOR
STRANDS

Paul D. Emerson, Media, Pa., assignor, by mesne assignments, to The Chemstrand Corporation, Philadelphia, Pa., a corporation of Delaware

Application February 15, 1951, Serial No. 211,014

10 Claims. (Cl. 68—5)

1 This invention relates to an improved apparatus for the treatment of strands and like materials. More particularly, the invention relates to a new and improved apparatus for treating natural, synthetic, or artificial yarns and monofilaments with fluid media in liquid or vapor condition in a substantially closed chamber during their travel from one point to another.

"Strand," as used throughout this specification and the appended claims, is intended to include all types of strands, threads, yarns, filaments, fibers, fibrous bundles, bundles of filaments or filamentary material, ribbons, bands, extruded wire, rods, and the like, etc.

The present invention is especially applicable to the treatment of yarns made from various types of materials, such as cotton, wool, flax, hemp, etc., regenerated cellulose, such as that produced from viscose, cuprammonium cellulose, and the like, cellulose ethers and esters, such as methyl cellulose, hydroxyethyl cellulose, ethyl cellulose, etc., cellulose nitrate, cellulose acetate, cellulose propionate, cellulose butyrate, mixed cellulose ethers and esters, vinyl resins, such as polyacrylonitrile, copolymers of acrylonitrile, polyethylene, polyvinyl chloride, copolymers of vinyl chloride with vinyl acetate or acrylonitrile, after-chlorinated vinyl polymers and copolymers, vinylidene polymers, such as polyvinylidene chloride, etc., and condensation polymers, such as polyamides and polyesters, and the like, etc.

The known apparatus for the treatment of strands with fluids in liquid or vapor condition during their travel from one point to another comprise a substantially closed chamber, into which the strands pass through orifices which have dimensions only slightly greater than those of the cross-sections of the strands in order to reduce loss of treatment fluid as far as possible. For example, it is customary to treat synthetic or artificial strands with steam for the purpose of altering their properties, such as by stretching the strands in an atmosphere of steam under pressure or by permitting the strands to shrink during the steam treatment.

However, threading of such apparatus presents quite a problem because it is necessary, each time that a fresh batch of materials or strands is to be treated, to open up the apparatus sufficiently to make it possible to pass the materials through the orifices by hand. This involves loss of treatment fluid and also loss of heat when the operation is one carried out at a superatmospheric temperature, particularly if it is necessary to allow the apparatus to cool before

it can be handled. Moreover, it takes up the time of the operators and involves an extra overhead charge on account of loss of output while the apparatus is standing idle.

To overcome these disadvantages, it has been the practice to thread the strands through the orifices by means of a hooked wire. This procedure also leaves much to be desired since it is time-consuming, there is always the possibility of damaging the orifices with the hooked wire, and in addition, the orifices must be of sufficient size to allow the passage of the hooked wire therethrough. This, of course, limits the size of the orifices to one which is greater than the minimum size possible, thus allowing the escape of more treating fluid than is desirable which has an adverse effect on the strands being treated. That is, there is a pressure drop across the orifices or openings and treating fluid, such as steam, escaping therethrough exerts a frictional effect on the strands passing through the orifices, which sets up an irregular and uncontrolled tension in the strands in addition to the tension exerted by any mechanical stretching devices. Therefore, it is desirable to keep the size of the orifices as small as possible.

It is a primary object of the present invention to provide a new and improved apparatus for the continuous treatment of strands with a fluid medium, in either liquid or vapor condition, which overcomes the hereinbefore mentioned difficulties and disadvantages.

Another object of the invention is to provide a new and improved apparatus for the continuous treatment of strands with a fluid medium which is easily laced or threaded at the start of operation, or whenever rethreading becomes necessary, while reducing the escape of fluid from the chamber to a minimum during operation.

Other objects and advantages of the present invention will be apparent from the description thereof hereinafter.

In general, the objects of the present invention are accomplished by passing a strand to be treated continuously through a chamber while at the same time passing a fluid medium, such as steam or super-heated steam, through the chamber. Preferably, the fluid medium is passed through the chamber in the same direction as the direction of travel of the strand. The strand enters the chamber through an entrance orifice or opening and leaves through an exit orifice or opening, said orifices being only slightly larger in size than the strand passing therethrough with the exit orifice being movably

mounted toward and away from the entrance orifice.

Since the present invention is applicable to numerous and different types of strand-treating apparatus, for simplicity the invention will be described in detail as the same is employed in connection with a strand stretching device or tube, it being understood that the preferred embodiment shown in the accompanying drawing is merely intended to be illustrative and the invention is not to be limited thereby, but only in accordance with the scope of the appended claims.

In the drawing,

Figure 1 is a sectional side elevation view of a strand stretching tube or chamber as it appears when ready for threading or lacing, and

Figure 2 is a sectional side elevation view of the apparatus of Figure 1 in operative position, i. e., with a strand passing continuously therethrough.

Referring to both figures of the drawing, which depicts a preferred embodiment of the invention, a strand 3 passes around a godet or wheel 4 and an associated lap-displacing guide 5, through a fluid medium treating chamber or tube 6, which may be made of glass, porcelain, iron, steel, copper, and the like, but preferably of metal which is resistant to the particular fluid being employed therein, through the elongated tube 7, which is preferably a capillary tube, and then about another godet or wheel 8 and its associated lap-displacing guide 9. The tube or chamber 6 may be wrapped or lagged with a suitable insulating material, such as asbestos, rock wool, cork, or the like, as shown by the dotted line 10. If desired, the tube may be jacketed and a heat interchanger liquid or gas, such as hot or cold water, steam, etc., passed therethrough. Godet 8 may be driven at the same, slower, or faster speed than godet 4, depending on whether shrinkage, stretching or neither is desired.

Threaded onto the strand entrance end of tube 6 is a cap 11 in the center of which a nozzle 12 is threadedly mounted, the leading, tapered portion 12a of which extends into the tube or chamber 6. There is a small opening or orifice 13 in the nozzle 12 which fans out into the funnel-shaped entrance opening 13a in that part of the nozzle positioned outside of the tube 6. Threaded onto the strand exit end of tube 6 is a retaining cap 14 which has an opening 15 in the center thereof.

Slidably mounted in chamber 6 is a member or piston or piston-like member 16 which has an opening 17 therein in perfect alignment with and corresponding in size to the inlet orifice 13. Opening 17 is in reality the exit orifice. The capillary tube 7 has a sliding fit in the opening 15 which serves as a guide-way and centering means for the tube 7, and threaded into the piston 16 so that the opening 1a in tube 7 is in perfect alignment with the opening 17 and inlet orifice 13. The opening 1a is preferably slightly larger than the opening 17 but it may be of the same size if desired. The length of the tube 7 should be at least equal to and preferably slightly greater than the distance from the outer face or wall 14a of cap 14 to the inner end of inlet opening or orifice 13. A portion of tube 7 should extend beyond the face 14a to enable one to grasp the same and also to place a vacuum line 20 thereon. The inlet orifice 13 and the exit orifice 17 may be varied in size depending upon the size of the strand or strands being treated. For best operation, i. e., preventing abrasion to the strands and reducing the escape of fluid treating medium to

a minimum, the inlet and exit orifices are one to three times the diameter of the strand or strands passing through them.

Steam or other fluid, which may be superheated depending upon the temperature desired in the chamber, is admitted to tube 6 through the conduit 18 connected to the top thereof and the exhaust steam and condensate, if any, is expelled from the tube through conduit 19 connected to the bottom thereof. When using a liquid for treating the strand, the direction of flow would preferably be reversed in order to fill the tube with the liquid. As shown, the direction of flow of the steam is concurrent with the direction of travel of the strand through the tube. To reverse the direction of flow, conduit 18 would be positioned adjacent cap 14 and conduit 19 positioned adjacent cap 11. The tube 6 may be of any desired length depending upon the contact time desired between the steam or other fluid media and the strand.

While steam has been specifically referred to in describing the apparatus, it is to be understood that the invention contemplates the use of other vapors, for example, acetone or acetone-air and acetone-steam mixtures, air, formaldehyde, chlorine, and other toxic, corrosive, or obnoxious gases, etc., and various liquids, such as water, alkalies, acids, organic solvents, and solutions of solids and gases in liquids.

As shown in Figure 1, the apparatus is in condition to be laced or threaded. That is, the piston 16 has been pushed through the tube 6, by pushing the capillary tube 7 inwardly, until it abuts against the portion 12a of nozzle 12. Now the inlet and exit orifices are in alignment and form one continuous opening. A portion of tube 7 still extends outwardly from tube 6. The strand 3 is directed around godet 4 and the lap-displacing guide 5 and directed through the opening 13a into orifice 13. A vacuum line 20 is placed over the end of tube 7 outside of tube 6 and the strand 3 is drawn through orifices 13 and 17 and through the opening 1a in tube 7. The vacuum line 20 is then removed from tube 7 and the strand 3 directed around the godet 8 and lap-displacing guide 9. Prior to moving the member 16 through the chamber into abutting relation with the nozzle 12, the steam or other fluid passing through the chamber preferably is cut off and is not allowed to pass through the chamber 6 again until the tube has been threaded or laced and member 16 has been returned to the fixed position shown in Figure 2. However, it is to be noted that the steam inlet conduit 18 is so positioned that the steam enters the chamber or tube behind member 16 when it is in abutment with nozzle 12. Therefore, in the embodiment shown, it is not necessary to cut off the steam or other fluid flowing through the chamber while threading the same because member 16 acts as a barrier and prevents the fluid from getting into the space 21 around nozzle 12 and thereby prevents any possibility of the strand 3 being deflected from the course desired, namely through the inlet and exit orifices 13 and 17. Then tube 7 is pulled outwardly until piston 16 abuts against the retaining cap 14, as shown in Figure 2. The pressure of the steam or other fluid medium helps to hold member 16 in the fixed position shown in Figure 2, in abutment with cap 14.

In the position shown in Figure 2, the capillary tube 7 helps to prevent the escape of fluid media from tube 6 as well as serving as a guiding means for strand 3 outside of the chamber or tube 6.

Various changes in the dimensions, other than those hereinbefore mentioned, may be made in the apparatus as desired. For example, tube 6 may be cylindrical or rectangular, or it may be increased or decreased in diameter, or shortened or lengthened. All of these changes depend upon the type of treatment and the particular strand being treated. If desired, the size or diameter of member 16 may be less than that shown so that it does not contact the inner wall of chamber 6. Member 16 would then serve only as a retaining means by abutting against cap 14 when tube 7 is moved to the position shown in Figure 2. However, the use of the piston-like member 16 as shown is preferred since it helps to center the tube 7 in chamber 6. The chamber 6 then acts as a guideway for member 16 which is in reality a centering means.

By means of the present invention, threading or lacing of strand treating tubes or chambers is greatly facilitated without opening the chamber and without increasing the size of the strand inlet and exit orifices. In fact, the present invention enables the use of the smallest possible inlet and exit orifices thus practically eliminating the loss of steam or other fluid media. By thus reducing the steam or fluid loss to such an appreciable extent, there results a more nearly constant pressure throughout the length of the tube which often permits lower operating pressures. The device is simple in construction. Numerous other advantages will be apparent to those skilled in the art.

It is to be understood that the drawing and description are merely intended to be illustrative and that changes and variations may be made without departing from the spirit and scope of the invention as defined in the appended claims.

I claim:

1. An apparatus for treating continuously moving strands with fluid comprising a fluid treating chamber having two end-walls therein, a strand-entrance orifice in one end-wall of the chamber, a member in the chamber mounted movably toward and away from the strand-entrance orifice, an opening in the member for passage of the strand therethrough, an opening in the other end-wall of the chamber, means slidably mounted in the said other end-wall opening and integrally attached to the member for moving the member in the chamber, said means having an opening therein for passage of the strand therethrough, means for continuously passing a strand through the chamber, and means for supplying fluid to the chamber, said fluid supplying means being positioned so as to allow the fluid to force the member in abutting relationship with the second-mentioned end-wall of the chamber.

2. An apparatus as defined in claim 1 wherein the chamber comprises an elongated straight tube.

3. An apparatus as defined in claim 1 wherein the means for moving the member is a tube, the opening in the tube being in alignment with the opening in the member.

4. An apparatus for treating continuously moving strands with fluid comprising a fluid treating chamber having two end-walls therein, a nozzle in one end-wall of the chamber and extending into the chamber, said nozzle having an opening

therein for the passage of a strand therethrough, a member in the chamber mounted movably toward and away from the nozzle, an opening in the member for passage of the strand therethrough, an opening in the other end-wall of the chamber, means slidably mounted in the said other end-wall opening and integrally attached to the member for moving the member toward and away from abutting relationship with the nozzle, said means having an opening therein for passage of the strand therethrough, means for continuously passing a strand through the chamber, and means for supplying fluid to the chamber, said fluid supplying means being positioned so as to allow the fluid to force the member into abutting relationship with the second-mentioned end-wall of the chamber.

5. An apparatus as defined in claim 4 wherein the chamber comprises an elongated cylindrical straight tube.

6. An apparatus as defined in claim 4 wherein the means for moving the member is a capillary tube, the length of which is greater than the distance between the inner face of the nozzle and the outer surface of the second-mentioned end-wall, said capillary being in alignment with the said other end-wall opening.

7. An apparatus as defined in claim 4 wherein the member is a piston.

8. An apparatus as defined in claim 7 wherein the means for moving the piston is a capillary tube, said capillary tube being larger than and in alignment with the opening in the piston.

9. An apparatus for treating continuously moving strands with fluid comprising a fluid treating chamber consisting of an elongated cylindrical straight tube having two end-walls therein, a nozzle in one end-wall of the chamber and extending into the chamber, said nozzle having an opening therein for the passage of a strand therethrough, a piston in the chamber mounted movably toward and away from the nozzle in sliding fit with the inner walls of the chamber, an opening in the piston for passage of the strand therethrough, an opening in the other end-wall of the chamber, capillary tube means slidably mounted in said other end-wall opening and integrally attached to the piston for moving the piston toward and away from abutting relationship with the nozzle, said capillary being larger than and in alignment with the opening in the piston, means for continuously passing a strand through the chamber, and means for supplying fluid to the chamber, said fluid supplying means being positioned so as to allow the fluid to force the member into abutting relationship with the second-mentioned end-wall of the chamber.

10. An apparatus as defined in claim 9 wherein the capillary tube means is greater in length than the distance between the inner face of the nozzle and the outer surface of the second mentioned end-wall.
